UNITED STATES PATENT OFFICE.

PAUL HANSON, OF WILD HORSE, COLORADO.

BUTTER-MAKING MACHINERY.

1,095,181.

Specification of Letters Patent. Patented Apr. 28, 1914.

Application filed December 22, 1911. Serial No. 667,332.

To all whom it may concern:

Be it known that I, PAUL HANSON, a citizen of the United States, residing at Wild Horse, in the county of Cheyenne and State 5 of Colorado, have invented a new and useful Improvement in Butter-Making Machinery, of which the following is a specification.

My invention relates to improvements in 10 butter making machinery and its object is to provide a combined churn and butter worker having the most improved features for churning cream and handling the resulting butter, and at the same time so construct it that it may be inexpensive in manufacture and simple in manipulation.

The structure of the churn body together 20 with its cover and cover lock and means for mounting it operably in its supporting frame and other details of construction constitute the subject matter of this invention.

In the drawings with which I have illustrated my invention and which form part of this specification, Figure 1 is an elevation, 25 part in section, showing the churn body mounted on its supporting frame; Fig. 2 is another elevation of the churn and support as shown in Fig. 1; Fig. 3 is a section on the line X—X, Fig. 1 showing the interior of 30 the churn receptacle; Figs. 4 and 5 are fragmentary sectional views on the line Y—Y, Fig. 2; Fig. 6 is a view in perspective of the lifting shelf; Fig. 7 is a sectional view of the support for the shelves; Fig. 8 35 is a detail of the stop button, and Fig. 9 is an end view of the butter worker showing the end plate.

In the above drawings I have shown a 40 churn body or receptacle A mounted rotatably on a supporting frame B and having within it a butter worker C. The butter worker C and body A being operable by a mechanism D including a pair of gears and an operating handle. A lifting shelf E is 45 positioned within the receptacle A and a door F of special construction is provided, giving access to the receptacle A.

The frame B consists of base parts 2 resting 50 on the floor on which the machinery stands and a pair of uprights 3 connected with each base part 2 and sloping together toward their upper extremity, a cross piece 4 being placed between the uprights 3 and connected thereto by bolts 5 passing through 55 the uprights and ends of the cross piece.

The upper ends of the pairs of uprights 3

are embraced by a casting 6 having a rib 7 lying between the uprights receiving a transverse bolt 8 connecting the uprights thereto. The rib 7 spaces the uprights constituting each pair apart and coacting with the bolt 8 materially strengthens the frame in a simple and effective manner. Castings 6 contain bearings 9 for the stud shafts 10 and 10'.

The churn body or receptacle A is a parallelepiped having ends 12, sides 14, a bottom 15 and a top 16, these terms being relative to the position of the churn body as illustrated in the drawings. The ends are inset each being formed with a tongue 13 on its edges fitting a groove 13' on the inside of the sides, top and bottom of the churn to form a liquid tight joint. At the ends of the sides and bottom are provided slats 17 which rest on the walls of the churn opposite to the ends 12. Tie-bolts 18 pass through the slats 17 near their ends and are provided with nuts 19 at their extremities for the purpose of tightening the bolts upon 20 the slats 17. These tie-bolts 18 assist in holding the walls of the churn together. By this means all of the walls of the churn may be readily pressed together to tighten 25 seams in the material of which they are 30 made.

In one of the sides 14 adjacent to the bottom 15 of the churn is provided an aperture closed by the plug 20 for drainage of the churn receptacle. A screen 21 of 35 meshed fabric covers the aperture on its inner side to prevent the passage of particles of butter fat out of the churn during the process of drainage. Washers 22 are provided beneath the nuts 19 on the slats 17 to protect the wood work of the slats.

The top 16 of the churn is provided with reinforcing pieces 23 which extend the full length of the churn and receive the head ends of two pairs of bolts 18 besides helping 40 to support the locking bars 27 of the door F. The door F consists of a body part 24 filling the space freely between the reinforcing pieces 23 and having cleats 25 adjacent to the ends 12 of the churn and extend through 45 the aperture in the top 16, being beveled at one side and at their ends to fit conveniently into the aperture. The cleats are fastened to the body 24 in any convenient manner, preferably by means of screws extending 50 through the body into the cleats.

Between the body 24 at its edges and the

top 16 of the churn is inserted strips of cork 26 extending entirely around the aperture or hatchway in the top and adapted when the cover is fastened on, to close the aperture tightly against the passage of liquid during the operation of the churn.

The door F is fastened in place on the churn by means of locking bars 27. One extremity of each bar 27 is socketed in a light 10 casting 28 attached to the reinforcing pieces 23 by screws 29 and the bolts 18. The opposite ends of the bars 27 are adapted to be engaged by a fastener 30 mounted on the opposite piece 23 and provided with a beveled rotatable catch 30' which is adapted to engage the ends of the bars 27 and force them tightly down upon the door F of the churn. The fastening parts 28 and 30 are simple in construction and readily replaced 15 when worn while the bars 27 may be made of wood or metal.

Within the receptacle A a lifting shelf E is provided extending from the side wall of the churn substantially to its axis and 20 adapted to intercept the entire contents of the churn at each revolution. The lifting shelf E is formed with end pieces 31 to which are attached slats 32 extending the full length of the churn. The slats have 25 beveled sides 33 directed downward in the normal position of the churn. The lifting shelf E is supported on cleats 34 fastened to the ends 12 of the churn by means of screws 35 or in any suitable manner. Lugs 30 36 on the upper surface of the cleats 34 fit into the openings between the slats 32 engaging the beveled faces of the slats to hold the lifting shelf E in position longitudinally of the cleats 34. The corners of the cleats 40 may be beveled to give a neat appearance to the churn and to assist in cleansing the interior. In each end 12 of the churn is provided a stop pin 37 which impinges on the extremities of the end pieces 31 and co-operate with the cleats 34 to prevent movement 45 of the lifting shelf E toward the axis of the churn.

A locking button 38 is mounted rotatably on the wall 14 of the churn by means of a 50 screw 39 or in any suitable manner so that its extremities 40, in the normal position of the button, impinge on the extremities of the end piece 31 opposite to the pins 37, in this way locking the lifting shelf E down 55 against the slats 34 and pins 37. The button 38 may be rotated out of its normal position with its longest diameter extending longitudinally of the churn to permit the raising of the lifting shelf E off from the slats 34 and its removal from the churn through the 60 hatchway.

Between the lower extremity of the lifting shelf E and the opposite wall 14 of the churn is mounted the butter worker C which 65 is provided with vanes 41 and extends nearly

the entire length of the churn receptacle being journaled on its ends to revolve within the receptacle.

At the operating end of the churn at which is located the operating mechanism D, 70 the butter worker C within the receptacle A, is provided on its end with a spider 42 attached thereto by suitable screws 43 and having on the axis of the worker C a square socket 44 adapted to the reception of a squared end 45' on a shaft 45 received therein to operate the butter worker. The shaft 45 is journaled in the end wall 12 of the churn in a casting 46 which carries the shaft 10 on which the churn is journaled, and carries without the churn a pinion 47. A packing washer 47' of yielding material such as leather is inserted between the squared head 45' and the casting 46 on the shaft 45 for the purpose of making a fluid tight 85 joint.

The opposite extremity of the butter worker C is provided with a block 48 (see Fig. 5) of hard wood socketed therein upon its axis and having a recess 49 in which is 90 received a pin 50 threaded in a casting 51 which is secured on one of the ends 12 of the churn. The pin extending through the casting is adapted to support one end of the butter worker and hold the squared end 45' 95 in the recess 44. A cross pin 52 is fixed in the head of the pin 50 to assist in adjusting it. A wear pin 53 is fixed in the end of the butter worker on its axis to resist end wear of the pin 50.

The castings 46 and 51 on which are fixed the shafts 10 and 10' journaling the churn, are formed with cross ribs 54 strengthening and lightening the castings. The castings are fastened to the ends 12 of the churn by 105 means of screws 55 or in any other suitable manner in such a position that the shafts 10 are upon the axis of the churn. The shafts 10 and 10' extend longitudinally of the axis of the churn, outward from its ends, 110 and are journaled in the castings 6 on the frame B as previously described. The shafts extend through the castings 6 and the shaft at the operating end of the churn is provided with a handle 56 fixed thereon by 115 means of a set screw 57. A collar 58 is fixed on the shaft 10' at the other end of the churn by means of a set screw 59. The operation of the handle 56 rotates the connected shaft 10 and the churn body A fixed 120 relatively thereto.

At the operating end of the churn, a gear wheel 60 is freely journaled on the shaft 10 between the castings 46 and 6, the bearing of the wheel extending into the casting 6 to 125 impart stability in operation. The shaft 10 is rigidly secured to casting 46 by pin 46'. The gear wheel 60 is provided with an internal gear face 61 having teeth meshing with the pinion 47 to rotate the butter 130

worker. Integral with the gear wheel 60 is a socket piece 62 in which is fixed a handle 63 by means of a bolt 64. The gear is formed of metal while the handle 63 may be 5 made of wood for ease in replacement.

A stop 75 in the form of a button is pivotally mounted by a bolt 76 upon one of the pairs 3 of uprights of the frame and is movable into and out of engagement between pairs of shoulders which are formed 10 by notches 77 in the end edges of the sides of the churn. The engagement by the stop with one notch is such as to hold the churn with its opening uppermost while the other engagement is such as to hold the churn at 15 an angle with its opening at one side. A lug 78 integral with the gear casting 60 is provided so that when the stop 75 is moved out of engagement with the churn A and into 20 the medial position illustrated by broken lines 75' in Fig. 1 it engages said lug 78 and prevents the revolution of the gear 60. Thus the operation of handle 56 while the lug 78 is engaged causes the butter worker 25 to operate at high speed.

It is evident that the rotation of the churn receptacle A may be secured by means of the operating handle 56 and that the handle 63 and gear 60 normally rotate with the 30 churn when the stop 75 is withdrawn from the position shown in Fig. 1 through friction of the parts. The rotation of the gear 60 with the churn produces no relative movement between the gear 60 and the pinion 35 47 and the butter worker C does not rotate on its axis. This is the normal position during the churning operation before the working of the butter has begun. To start the operation of the butter worker C 40 the stop 75 is moved into engagement with the lug 78 as illustrated in Fig. 1 by broken lines 75'. Thus holding gear 60 stationary and operating the pinion 47 while the churn revolves or the handle 63 can be engaged by 45 hand holding the gear 60 stationary while the stop 75 is moved completely out of engagement with all operating parts. Upon the starting of the rotation of the churn under these conditions the churn revolves 50 with relation to the gear 60 and the pinion 47 is rotated thereby thus operating the butter worker C fixed thereto.

The position of the pinion 47 within the gear 60 causes the rotation of the butter 55 worker C in a direction opposite to the churn body A and the vanes 41 of the butter worker C are formed with their edges projecting in the direction of rotation of the butter worker in the normal operation 60 of the churn. The lifting shelf E is so positioned that in the rotation of the churn the contents thereof are thrown by said shelf upon the butter worker C and against the vanes 41. The pinion 47 being smaller than 65 the gear 60 causes the butter worker to ro-

tate at a relatively high speed to the churn during its operation. The butter worker being eccentric to the axis of the churn causes efficient and effective results.

In accordance with the patent statutes I 70 have described the principles of operation of my invention together with the apparatus which I now consider to represent the best embodiment thereof but I desire to have it understood that the construction shown is 75 only illustrative and that the invention can be carried out by other means and applied to uses other than those above set forth within the scope of the following claims.

Having described my invention, what I 80 claim as new and desire to protect by Letters Patent is:—

1. In a device of the class set forth, a supporting frame, and a churning receptacle mounted rotatably on said frame, said receptacle having closed sides and ends, a cover removably fixed upon one side of said receptacle, a lifting shelf extending from a side wall in said receptacle to near its axis and adapted to intercept the entire contents 90 of said receptacle at each revolution, stop pins through the ends of said receptacle obstructing the shelf from movement toward the axis of said receptacle, cleats on the ends of said receptacle supporting said shelf and 95 clamps movably secured upon said ends and adapted to impinge upon said shelf and detachably hold it down upon said cleats and against said stop pins.

2. In a device of the class set forth, a supporting frame, a receptacle rotatable on said frame, said receptacle having closed sides and ends, a cover removably fixed upon one side of said receptacle, a lifting shelf within said receptacle adapted to assist in agitating the contents thereof, means for rotating said receptacle, a butter worker journaled eccentric to the axis of rotation of said receptacle, means for rotating said butter worker interconnected with said operating means for said receptacle and means interposed between the actuating mechanism for driving said receptacle and the actuating mechanism for driving said butter worker, said interposed means being movable into 105 three positions whereby said receptacle may be held stationary while the interposed means is in one position, the butter worker caused to revolve on its own axis at high speed during the revolution of said receptacle when said interposed means is in medium position, and said parts free from positive engagement when said interposed means is in the remaining position.

3. In a device of the class set forth, a supporting frame, a receptacle having closed sides and ends, shafts carried by said receptacle and journaled in said supporting frame, means for revolving said shafts causing the revolution of said receptacle, gear- 125

ing carried by one of said shafts, a pinion adapted to be driven by said gearing, a butter worker in said receptacle connected with said pinion to be driven on an axis eccentric to the axis of said receptacle, a handle carried by said gearing whereby said gearing may be held stationary and causing the revolution of said butter worker upon its axis and a stop movable into the path of said 10 receptacle to hold the same stationary and movable out of the path of said receptacle and into the path of said gearing to hold said gear stationary thereby causing the revolution of said butter worker on its axis 15 4. In a device of the class set forth, a supporting frame, a receptacle journaled in said frame having closed sides and ends and a cover removably fixed upon one side of said receptacle, a butter worker journaled 20 in said receptacle eccentric to the axis of the receptacle, a drive gear journaled upon the axis of said receptacle, a pinion carried by said butter worker and driven by said gear and a stop movably mounted upon said 25 frame, said receptacle being shouldered whereby said stop may be moved into engagement therewith to hold the receptacle with its door opening uppermost or at an angle with its door opening at one side and 30 said stop being movable out of engagement with said receptacle and into engagement with said gear whereby the butter worker may be revolved upon its axis during the revolution of said receptacle. 35 5. In a device of the class set forth, a supporting frame, a receptacle having end walls, a shaft carried by said end walls and journaled in said frame, a butter worker in said receptacle revoluble about an axis eccentric to the axis of said receptacle, a gear journaled upon one of said 40 shafts, means for holding said gear stationary out of engagement with said gear to permit said gear revolving, a second shaft journaled in one end of said receptacle and having an inner squared end 45 movably socketed in one end of said butter worker, a washer interposed between said end of said butter worker and the adjacent end of said receptacle and mounted upon said second shaft to produce a liquid tight 50 joint, a pinion carried by said second shaft having its teeth meshing with the teeth of said gear and a spindle having its outer end threaded into the opposite end of said receptacle and its inner end projecting into the said receptacle, said butter worker having a journal 55 recess in one end in which the inner end of said spindle is adapted to journal and its other end having a square socket adapted to receive the squared end of said second shaft for the purposes specified. 60 6. In a device of the class set forth, a

receptacle, a butter working roller within said receptacle, a revoluble shaft detachably secured to the end of said roller and journaled in a wall of said receptacle, a packing 65 washer interposed between an end of said roller and the wall of said receptacle in which said shaft is journaled, and a stationary shaft in a wall of said receptacle upon which the other end of said roller is 70 journaled, said stationary shaft being adjustable endwise to thrust said roller against said packing washer whereby a fluid tight joint is effected.

7. In a device of the class set forth, a 75 supporting frame and a receptacle mounted rotatably on said frame, said receptacle having closed ends and sides, a cover removably fixed upon one side of said churn, a lifting shelf within said receptacle adapted to agitate the contents of said receptacle, interconnected gearing for revolving said butter worker actuated by the revolution of said receptacle, part of said gearing being free to remain stationary while the receptacle revolves and a stop movable into the path of said receptacle to hold the same stationary and also movable out of the path of said receptacle and into the path of part of said gearing whereby said butter worker is 90 caused to revolve through the revolution of said receptacle.

8. In a device of the class set forth, a supporting frame, a receptacle having end and side walls, shafts carried by said end 95 walls and journaled in said frame, a butter worker in said receptacle revoluble about an axis eccentric to the axis of said receptacle, a gear journaled upon one of said shafts, means for holding said gear stationary out of engagement with said gear to permit said gear revolving, a second shaft journaled in one end of said receptacle and having an inner squared end, a pinion carried by said second shaft having its teeth 100 meshing with the teeth of said gear and a spindle having its outer end threaded into the opposite end of said receptacle and its inner end projecting into the said receptacle, said butter worker having a journal 105 recess in one end in which the inner end of said spindle is adapted to journal and its other end having a square socket adapted to receive the squared end of said second shaft for the purposes specified. 110

In testimony whereof, I have signed my name to this specification, in the presence of two subscribing witnesses.

PAUL HANSON.
